CLAIM

The ornamental design for a motorcycle wheel, as shown and described.

DESCRIPTION

FIG. 1 is a right side head on view of the motorcycle wheel without the brake disc, according to the present invention;

FIG. 2 is a left side head on view of the motorcycle wheel without the brake disc.

FIG. 3 is a right side perspective view of the motorcycle wheel without the brake disc.

FIG. 4 is a left side perspective view of the motorcycle wheel without the brake disc.

FIG. 5 is a right side head on view of the motorcycle wheel with the brake disc assembled.

FIG. 6 is a left side head on view of the motorcycle wheel with the brake disc assembled.

FIG. 7 right side perspective view of the motorcycle wheel with the brake disc assembled.

FIG. 8 is a left side perspective view of the motorcycle wheel with the brake disc assembled.

FIG. 9 is a head on enlarged view of the brake disc of the motorcycle wheel.

FIG. 10 is an exploded view of the assembly of the motorcycle wheel; and,

FIG. 11, removed from the motorcycle wheel for ease of disclosure, is a close up view of the palm tree design of the motorcycle wheel.
